Specification for Design.

Patented Feb. 23, 1915.

Application filed October 20, 1914. Serial No. 867,659. Term of patent 3½ years.

To all whom it may concern:

Be it known that I, ERNEST G. H. SCHENCK, a subject of the King of Belgium, residing at Wilton, Connecticut, United States of America, have invented a new, original, and ornamental Design for Diamonds or other Similar Precious Stones, of which the following is a specification, reference being had to the accompanying drawing, forming part thereof.

In the drawing Figure 1 is a view of one

side of the diamond and Fig. 2 a view of the other side cut in accordance with my new design.

I claim:

The ornamental design for a diamond or other similar precious stone, as shown.

ERNEST G. H. SCHENCK.
